A. C. IONIDES, JR.

FLUID CONTROLLING DEVICE

Filed Nov. 27, 1922

UNITED STATES PATENT OFFICE.

ALEXANDER CONSTANTINE IONIDES, JR., OF LONDON, ENGLAND.

FLUID-CONTROLLING DEVICE.

Application filed November 27, 1922. Serial No. 603,719.

To all whom it may concern:

Be it known that I, ALEXANDER CONSTANTINE IONIDES, Junior, a subject of the King of Great Britain and Ireland, and residing at 34 Porchester Terrace, London, W. 2, England, have invented certain new and useful Improvements in or Relating to Fluid-Controlling Devices, of which the following is a specification.

10 This invention relates to fluid controlling devices of the type having a movable member such as a floating bell or other appliance which forms a partition between two compartments, each of which contains a valve 15 which controls the entrance of fluid thereto, said valves being simultaneously actuated to perform opposite functions by the movement of the partition in such a manner that a constant relationship is maintained between the pressures of the fluids 20 leaving the compartments.

To increase the sensitiveness of the control exerted by such devices, one portion of the necessary moving weights has been arranged to balance another portion but even this does not wholly obviate the use of certain additional parts such as direction reversing means, the weight of which, particularly in larger sized apparatus, contributes to the inertia of the total moving mass.

The object of the present invention is to remove the foregoing objections and to provide improved devices of the type indicated.

The invention consists in a fluid controlling device of the type indicated, in which the weight of the moving parts is balanced by a spring or other resilient appliance.

The invention further consists in a fluid controlling device in accordance with the preceding paragraph, and comprising in combination an upright casing, a bell movable in a liquid seal or other movable partition dividing said casing into an upper and lower compartment, an inlet branch or conduit entering each compartment and each provided coaxial with and connected to said partition with a pressure balanced or double seated valve which controls the admission of a separate fluid to each compartment, an outlet from each compartment permitting the exit of fluid therefrom and a spring or other resilient appliance supporting the weight of said partition and

the valves connected thereto and permitting movement of the whole under the pressures acting upon the partition to maintain within very narrow limits a constant relationship between the pressures of the fluids leaving the compartments.

The invention also consists in improvements in or relating to fluid controlling devices as hereinafter described.

The accompanying drawing shows by way of example a convenient embodiment of the invention taking the form of a vertical cylindrical casing which is divided into two compartments, *a* being the upper and *b* the lower. These are separated by means of a movable partition in the form of a gas bell *c* enclosed in an annular sealing tank *d* formed round the inside of the casing between the upper and the lower ends thereof.

The casing in the embodiment illustrated consists of three hollow cylindrical bodies, *e*, *f*, *g* which are each flanged at both ends and bolted together in sequence *e*, *f*, *g*.

In the central cylinder *f* of the three, a fourth hollow body is positioned, this body taking the form of an inverted cylindrical pan *h* having a flange *h'* the outside diameter of which is equal to the diameter of the casing flange and which may be fastened between the flanges of the lower and middle cylinders *f* and *g*, as by welding to one of the flanges, with the cylindrical portion *h₅* of the pan extending upward within the middle cylinder, thus providing an annular space which forms the liquid seal for the movable gas bell *c* positioned in the tank *d* and the top of which forms a partition which divides the casing into an upper compartment *a* and lower compartment *b*.

The inverted cylindrical pan *h* may conform at its upper part to the interior surface of the gas bell *c* and thus form a means of support when the gas bell *c* is in its lowest position. In the top of the pan a central aperture *h₂* is provided allowing the fluid in the lower compartment *b* to have access to the underside of the gas bell *c* for the purpose of actuating the same. When in its highest position the top of the gas bell *c* coincides approximately with the flanges of the middle *f* and upper *e* of the three cylindrical bodies, and between these flanges a disc-shaped member *h₃*, the under surface of which conforms to the upper

surface of the gas bell c , is inserted. This disc will form a stop for the bell in its uppermost position and in common with the top of the inverted pan h it is provided with 5 an aperture h_4 which permits the fluid in the upper compartment a to act upon the upper surface of the bell. The purpose of the positioning stops or discs h and h_3 for the upper and lower extreme positions of the 10 bell is to provide a support and protection in the event of the bell being accidentally subjected to any excessive fluid pressure which might damage the light thin material of which it is preferably constructed.

15 The compartments a and b are provided with internal valve chambers k and k' , suitably formed by inlet conduits penetrating the walls of the hollow cylinders e and g and extending sufficiently far enough into 20 the interior thereof to allow for valve apertures k_1 , k_2 and k_3 , k_4 in the top and bottom of each conduit being provided concentric with the axis of the movable bell c .

25 A pressure balanced or double seated valve k_4 for the air is provided in the valve chamber k and a corresponding valve k_5 of suitable dimensions for the gas is provided in the casing k_1 , each valve having two 30 discs which may be of equal or substantially equal size as shown at k_6 , k_6 for the air valve and at k_7 , k_7 for the gas valve, the relationship between the diameters of the air and gas valves depending upon the kind of gas employed.

35 The double seated valve k_4 fitted in the upper or air valve chamber k is adapted to close or shut off when moved in a downward direction and the double seated valve k_5 in the lower or gas valve chamber k_1 will 40 shut off or close when caused to move in the upward direction.

45 A central rod l coinciding with the axis of the casing and concentric with the valve apertures and the gas bell is connected to the lower double seated valve, the gas bell and the upper double seated valve, the connection being conveniently of a type adaptable to adjustment so that both the valves and the bell may be adjusted to function 50 correctly with their co-operating parts, such as the apertures k_2 and k_3 and the tank d .

55 The rod l which carries the valves and the gas bell is preferably guided for vertical movement at the bottom by means of a guide piece m which is securely fastened to the bottom cover q_1 of the casing. It also passes through a guide m_1 at the top of the casing which may be held positioned 60 by supports (not shown) which may project from the sides of the casing. The end of the central rod projects above the top guide, as shown.

65 A concentric extension p of conveniently reduced cross-sectional dimensions is con-

nected by the cover q to the upper end of the casing, and within the extension p is suspended a helical tension spring m_2 which is connected to the above mentioned projecting upper end of the central rod, as for 70 example by means of a hook and eye arrangement m_3 . The upper end of the helical spring is connected to a central member r which passes through a guide m_4 having a square or like multisided aperture to 75 prevent rotational movement of the upper part of the member r .

The central member r passes through the cover p' of the extension p and the projecting part is screw-threaded and provided with a readily turnable nut or hand-wheel m_5 by means of which the central member r may be raised or lowered to effect any necessary adjustment.

The helical spring m_2 is designed so as 85 to support the entire weight of the two valves and the bell when each of these elements is in the central position of its travel, and is designed to allow movement in either direction under variations of pressure so 90 as to permit the closing of one valve and the full opening of the other, when moved in either direction. The spring will be so proportioned that with a very small difference of pressure acting on the bell it will 95 permit the necessary movement of the valves and as the moving weights are reduced to the double seated valves and the bell together with the central connecting member the inertia of the mass is reduced 100 to a minimum and the sensitiveness of the controllable device is correspondingly increased.

The valves and the bell may be of the lightest possible construction to withstand 105 the stresses to which they are subjected and as previously explained the stop or positioning discs which are provided on both sides of the bell may be set closely adjacent to its extreme positions so as to prevent the 110 possibility of injury to it by the action of any accidental increase of pressure upon it.

115 Outlet openings n and n_1 are provided in the upper and lower compartments of the device and to these are connected the mains or the like which supply the two fluids to the appliances in which they are used. The device is particularly applicable to controlling the supply of gas and air at substantially equal or constantly related pressures 120 to combustion appliances of the type in which combustion takes place within a closed chamber under a slight back pressure resulting from the discharge of the products of combustion to atmospheric pressure at a lower level than the combustion region, thus ensuring the absence of any suction effect which might draw in the surrounding air and so alter the relation 125 between the quantities of the constituents.

taking part in the combustion reaction, such combustion appliances being also, if desirable, jacketed with the hot products of combustion in order to prevent heat losses and also where required provided with test flame or like appliances for determining the proportions of the mixture by combustion of a very small proportion thereof.

10 It is to be understood that the construction hereinbefore described is given by way of example and that modifications and additions may be made thereto without in any way departing from the spirit of this invention.

Having now described my invention, what I claim as new and desire to secure by Letters Patent is:—

1. A fluid-controlling device having in combination a movable partition, two double-seated valves each one of which regulates one of two separate fluids controlled by said device, means whereby each valve is connected directly to said movable partition and when moving travels simultaneously an equal distance in the same direction, and means for resiliently balancing the weight of the moving parts.

2. A fluid-controlling device having in combination a movable gas bell, two double-seated valves each one of which regulates one of two separate fluids controlled by said device, means connecting each valve directly to said movable bell so as to move in unison therewith and a spring device for resiliently balancing the weight of the moving parts.

3. A fluid-controlling device having in combination an upright casing, a movable partition dividing said casing into an upper and lower compartment, an inlet branch entering each compartment, a double-seated valve controlling the admission of a separate

fluid from each branch to each compartment, means whereby each valve is connected directly to said movable partition and when moving travels simultaneously an equal distance in the same direction, an outlet from each compartment and a resilient appliance supporting the weight of said partition and the valves connected thereto and permitting movement of the whole under the pressures acting upon the partition.

4. A fluid-controlling device comprising in combination a casing, a movable partition forming an upper and a lower compartment therein, a conduit entering each compartment, an independent two-disc valve with the pressure acting in an opposite direction on each disc to control the passage of fluid from each conduit to its respective compartment, an outlet from each compartment, means directly connecting each valve to said partition so as to move in unison therewith and a resilient device supporting all the moving parts.

5. A fluid controlling device having in combination an upright casing, a bell movable in a liquid seal dividing said casing into an upper and lower compartment, a conduit entering each compartment, a double-seated valve controlling the admission of a separate fluid from each conduit to each compartment, means whereby each valve is connected directly to said movable bell and when moving travels simultaneously an equal distance in the same direction, an outlet from each compartment and a spring supporting the weight of said bell and the valves connected thereto and permitting movement of the whole under the pressures acting upon the opposite sides of the top of said bell.

In testimony whereof I have signed my name to this specification.

ALEXANDER CONSTANTINE IONIDES (Junior).
